(57) **CLAIM**

The ornamental design for fascia, as shown and described.

DESCRIPTION

FIG. 1 is a partial perspective view of my design for fascia;
FIG. 2 is a side elevational view thereof;
FIG. 3 is a sectional view taken along line 3—3 of FIG. 2;
and,
FIG. 4 is a sectional view taken along line 4—4 of FIG. 2.
The fascia is broken on the ends to indicate indefinite length.
